FOUNDATION GARMENT

Mack Kahn, Cedarhurst, N. Y., assignor to Artistic Foundations, Inc., New York, N. Y., a corporation of New York

Application July 12, 1941, Serial No. 402,078

2 Claims. (Cl. 2-37)

This invention relates to a foundation garment. The purpose of a foundation garment is to mold the figure of the wearer as comfortably as possible. One trouble with ordinary foundations is that they have a tendency to ride up when the wearer sits down. When the bottom of the garment is attached to the stockings by garters this tends to start runs. Moreover, after the wearer stands up she has to pull down the lower edge of the garment to restore it to its proper position.

It has been proposed to avoid these troubles by employing a rear panel which over-lies the seat of the wearer and which is made of material which stretches up and down but not across, the rear panel being connected to side panels which stretch crosswise, and, in some instances, also up and down. In actual practice it has been customary to make the rear panel of woven material in which the vertical strands are made of rubber wound with yarn. The side panels have usually been made of similar material with the rubber threads extending horizontally, or both horizontally and vertically. Although such foundation garments possess proven advantages, the use of so much rubber thread wound with yarn makes the garments relatively thick as well as expensive.

I have found that a foundation garment which has excellent figure molding characteristics, which lies flat against the seat, which holds its position on the figure, and which is exceptionally comfortable, can be made by constructing the rear panel mainly of non-elastic material joined to a relatively small section of material which is elastic in an up and down direction. Most specifically, I have found that the desired advantages can be obtained by providing a non-elastic section over-lying the seat of the wearer and by connecting a relatively small, vertically elastic section to the top of the first-mentioned section. In its preferred form, the rear panel of my garment includes a third section connected to the top of the second section and being elastic crosswise of the wearer.

Other features, objects and advantages of my invention will become apparent or will be pointed out in connection with the following detailed description of one preferred form of foundation garment embodying my invention, reference being had to the accompanying drawing wherein:

Fig. 1 is a perspective view showing the front and right side of the garment as worn on the figure;

Fig. 2 is a rear view of the same garment; and

Fig. 3 is a side view of the same garment. The foundation garment illustrated in the drawing includes a front panel 5 made of any suitable non-elastic material. A triangular gusset 6 which is elastic across the wearer is sewed into the front panel as shown. Brassière pockets 7 and 8 are sewed to the panel 5, and the usual shoulder straps 9 and garter straps 10 are provided.

A pair of similar side panels 11 are connected to the front panel 5. In order to allow the garment to be put on easily a zipper 12 is inserted between the panels 5 and 11 at one side of the garment. Each of the panels 11 is preferably made of woven material having elastic strands extending generally horizontally as indicated by the double arrows. These panels are non-elastic vertically. The panels 11 preferably terminate along edges 13 which are connected to side panels 14 of non-elastic material. The front edges of panels 14 are connected to the front panel 5 and to the brassière pockets 7 and 8.

To the rear edges of the side panels 11 and 14 there is sewed a rear panel 15 which includes a section 16 adapted to over-lie the seat of the wearer, the lower edge of this section lying below the buttocks. This section is made of non-elastic material, preferably a thin yet firm woven fabric. The side edges of this section are preferably curved so that its widest part lies about in the middle. The upper edge 17 preferably curves downwardly from either side toward the center of the back.

Secured to the upper edge 17 of the section 16 is a section 18, the side edges of which are sewed to the adjacent edges of the panels 14. This section 18, which is preferably made of woven fabric, is elastic vertically, but non-elastic horizontally. It possesses sufficient elasticity so that it permits the section 15 to retain its proper position when the wearer sits down. The proper amount of stretch can be determined from measurements of the figure standing and seated.

In the garment illustrated the edge 17 lies a little above the hips of the wearer and the section 18 lies above the edge 17 at the small of the back. The invention in its broader aspects is not, however, limited to this location of the section 18.

Connected to the upper edge 19 of the section 18 is a section 20 made of material which is elastic horizontally, but non-elastic vertically. The side edges of this section are sewed to the adjacent edges of the side panels 14. By combining this horizontally elastic panel with the vertically elastic panel 18, and with the non-elastic

panels 14, a good up-lift is obtained and at the same time easy breathing is permitted.

Although my invention has been described in connection with the particular embodiment shown, it will be understood that it may be incorporated in garments which do not include a brassière portion.

The terms and expressions which have been employed are used as terms of description and not of limitation, and there is no intention, in the use of such terms and expressions, of excluding any equivalents of the features shown and described, or portions thereof, but it is recognized that various modifications are possible within the scope of the invention claimed.

What I claim is:

1. A combination foundation garment of the character described composed of a front panel, a rear panel, and two side panels connected between the opposite edges of the front and rear panels, the front panel including brassière portions, the side panels including portions at the sides of the hips which are elastic horizontally but not vertically and inelastic portions connected to the brassière portions, and the rear panel including three generally rectangular sections arranged one above the other and having their adjacent edges secured together, the bottom sec-

tion being composed entirely of inelastic material and extending from a lower edge below the buttocks to an upper edge lying approximately at the waistline, the middle section being composed of vertically elastic horizontally inelastic material, and the top section being composed of horizontally elastic vertically inelastic material.

2. In a garment of the character described including side panels which are elastic horizontally at the hips, a rear panel the side edges of which are co-extensive with and joined to the side panels, said rear panel consisting of three generally rectangular sections arranged one above the other and having their adjacent edges secured together, the bottom section being composed entirely of inelastic material and extending from the lower edge of the garment to approximately the waistline, the middle section being composed of material which is vertically elastic and horizontally inelastic, and the top section being composed of material which is horizontally elastic and vertically inelastic, whereby the upward pull on the middle section is partially relieved by the stretching of the top section so that the stretching of the middle section is facilitated when the wearer bends forward.

MACK KAHN.
